UNITED STATES PATENT OFFICE.

JAMES PATTERSON, OF ROCKWELL, FLORIDA.

RAIL-CLAMPING DEVICE.

1,024,648.

Specification of Letters Patent.

Patented Apr. 30, 1912.

Application filed August 2, 1911. Serial No. 642,015.

To all whom it may concern:

Be it known that I, JAMES PATTERSON, a citizen of the United States, residing at Rockwell, in the county of Marion and 5 State of Florida, have invented new and useful Improvements in Rail-Clamping Devices, of which the following is a specification.

An object of the invention is to provide 10 a device for rigidly clamping rails to rail-way ties.

My invention embodies among other features, a structure in which the clamping members thereof can be adjusted so that the 15 force clamping the rail to the tie can be increased or decreased, my device being so arranged that a rail can be easily and quickly disconnected from a tie for the purpose of repairing the same or inserting a new rail.

20 To accomplish the desired result, use is made of a tie provided with a recessed end flange in which the rail is adapted to seat with one side of the web of the rail abutting against the end of the flange, slotted side 25 flanges formed on the tie, a clamping bar pivotally mounted in the slots of the side flanges and adapted to engage the other side of the web of the rail, a wedge for insertion in the slots of the said side flanges 30 and having one side thereof abutting against the clamping bar, the other side of the wedge being in engagement with a brace formed on the tie and means for operating the said wedge for increasing or decreasing 35 the clamping engagement of the clamping bar with the said rail.

Reference is to be had to the accompanying drawings constituting a part of this specification, in which similar characters of 40 reference denote corresponding parts in all the views and in which—

Figure 1 is a perspective view of one of my ties, showing the same in applied position. Fig. 2 is a vertical longitudinal section through the tie, taken substantially on the line 2—2 in Fig. 1. Fig. 3 is a vertical sectional view taken on the line 3—3 in Fig. 1. Fig. 4 is a vertical sectional view taken on the line 4—4 in Fig. 1. Fig. 5 is 50 a fragmentary sectional view taken on the line 5—5 in Fig. 1.

Referring more particularly to the views, I provide a tie 10 having end flanges 11 provided with recesses 12, rails 13 being adapted 55 to rest on a base 14 of the tie 10 with portions of the bases of the rails reposing

within the recesses 12 and with one of the webs of each of the rails abutting against the inner face of each of the flanges 11.

Formed on the tie 10 and projecting outwardly from the sides thereof are side flanges 15 provided with vertically extending slots 16 and an upwardly extending brace 17 is formed at one end of the side flanges 15 and extends transversely to the 60 tie 10. A clamping bar 18, consisting of a head 19 and spaced depending extensions 20, is mounted on the side flanges 15 with the extensions 20 passing through the slots 16, a bolt 21 being passed transversely 65 through the tie 10 and through apertures in the extensions 20 to pivotally retain the clamping bar 18 in engagement with the tie 10, the head 19 of the clamping bar being adapted to engage one side of the web 70 of each of the rails 13. A wedge 22, consisting of a head 23 and spaced extensions 24 is mounted between the brace 17 and the clamping bar 18 with the extensions 24 of the wedge passing through the slot 16 of 75 the side flanges 15. A set screw 25 is mounted to extend through the brace 17 to engage a side of the head 23 of the wedge 22 and a second set screw 26 is mounted to extend through one of the side flanges 15 to 80 engage one of the extensions 24 of the said wedge 22.

In the use of my device, the set screws 85 25 and 26 are moved out of engagement with the wedge 22 so that the clamping bar 90 19 can be moved to unclamping position and the rail 13 is then extended across the tie 10 with the base of the rail reposing upon the base 14 and with one portion of the base of the rail extended into the recess 95 12, one side of the web of the rail being engaged by a side of the end flange 11. The clamping bar 18 is now swung so that the head 19 thereof will engage the other side of the rail and then by operating the set 100 screws 25 and 26 the wedge 22 will move the clamping bar 18 into further engagement with the web of the rail 13 and rigidly secure the same to the tie 10, it being understood that a side 27 of the head 19 will 105 lie against one side of the base of the rail.

With the use of the device described in connection with rails, the said rails will be retained in rigid position relatively to the ties and can be easily and quickly removed 110 from the ties, while at the same time when the rails are rigidly clamped to the ties any

lateral movement of the rails will be prevented by the various members of my device coöperating to retain the rail in rigid position.

5 Having thus fully described the invention, what I claim as new, is:—

1. A rail clamping device comprising a tie, an end flange formed on the tie and provided with a recess adapted to receive a rail with one side of the web of the rail abutting against the said end flange, side flanges formed on the said tie and provided with slots, a brace extending transversely to the tie at one end of the said side flanges, 10 a clamping bar pivotally mounted on the said tie with portions of the said clamping bar extending through the slots in the said side flanges and another portion of the said clamping bar for engagement with the other 15 side of the web of the rail, a wedge for engagement with the said brace and said clamping bar and set screws mounted to extend through the said brace and through one of the said side flanges to engage the said 20 wedge for operating the same to move the said clamping bar into clamping engagement with the said rail.

2. A rail clamping device comprising a tie, an end flange formed on the tie and provided with a recess adapted to receive the rail with one side of the web of the rail abutting against the said end flange, side flanges formed on the said tie and provided with slots, a brace extending transversely to the tie at one end of the said side flanges, a clamping bar pivotally mounted on the said tie with portions of the said clamping bar extending through the slots in the said side flanges and another portion of the said 30 clamping bar for engagement with the other side of the web of the rail, a wedge for engagement with the said brace and said clamping bar and adjusting means mounted on the said tie for operating the said wedge 35 to move the said clamping bar into clamping position with the said rail.

3. A rail clamping device comprising a tie, an end flange on the said tie, side flanges on the said tie, a clamping bar pivotally mounted on the said tie and engaging the 40 said side flanges, a head on the said clamping bar for engagement with a rail mounted 45

to abut against the said end flange and a wedge for engagement with the said tie and the said clamping bar to retain said clamping bar in clamping position with the said rail.

55

4. A rail clamping device comprising a tie, an end flange on the said tie, side flanges on the said tie, a clamping bar pivotally mounted on the said tie and engaging the said side flanges, a head on the said clamping bar for engagement with a rail mounted to abut against the said end flange and means mounted on the said tie and engaging the said clamping bar for retaining the said clamping bar in clamping engagement with the said rail.

60

5. A rail clamping device comprising a tie, an end flange on the said tie and adapted to be engaged by a rail, a clamping bar mounted to swing on the said tie and capable of being moved into clamping engagement with the said rail, a wedge for engagement with the said tie and the said clamping bar 70 and set screws to move the said clamping bar into clamping engagement with the said rail.

75

6. A rail clamping device comprising a tie, an end flange on the said tie and adapted to be engaged by a rail, a clamping bar mounted to swing on the said tie and capable of being moved into clamping engagement with the said rail, a wedge for engagement with the said tie and said clamping bar and 80 means for operating the said wedge to move the said clamping bar into clamping engagement with the said rail.

85

7. A rail clamping device comprising a tie, an end flange on the said tie and adapted to be engaged by a rail, a clamping bar mounted to swing on the said tie and capable of being moved into clamping engagement with the said rail and means engaging the said tie and the said clamping bar for retaining the said clamping bar in clamping engagement with the said rail.
